FELTING AND/OR FULLING MACHINES

Edward W. Smith, Melrose, Mass.

Application March 9, 1955, Serial No. 493,133

14 Claims. (Cl. 28—5)

The present invention relates to improvements in felting and/or fulling machines and more particularly to an improvement for use in connection with a torsionally oscillating rotating roll such as is described more fully in my United States Patent No. 2,604,503.

In the use of the unit described in United States Patent No. 2,604,503 it has been the practice to arrange four or more accessory rolls around the torsionally oscillating rotating roll in such a way that they press against the periphery of the torsionally oscillating roll. The goods to be treated are then passed between the pressure rolls and the oscillating roll as the latter is rotated and the goods are subjected to a very rapid vibratory treatment as they pass successively under each of the pressure rolls before leaving the machine. The goods may, or may not, be wetted during the above treatment depending upon the action desired on them.

Experience has indicated that the majority of the above-mentioned treatment takes place as the goods pass between the pressure rolls and the oscillating roll about which they are disposed, and that little if any effect is produced during the time the goods are in contact with the oscillating roll but not being forced against it by the pressure rolls. In cases where the goods require more treatment than can be effected by a single passage between the four pressure rolls and the oscillating roll in the open width, increased amounts of treatment may be brought about either by increasing the number of pressure rolls, repeating the treatment by successive passes through the machine, or by using a battery of machines through which the goods successively pass. In certain cases this method of procedure is inconvenient and it is this situation which the present invention is designed to correct.

As hereinbefore stated, the treatment effected appears to take place during the period when the goods are passing between the pressure rolls and the oscillating roll, but not at other times even though the goods may be in intimate contact with the oscillating roll. While it is obvious that an increased amount of treatment in a given machine could be attained by increasing the number of pressure rolls there is a very practical and rather low limit to the number of pressure rolls which can be provided because of lack of space. In the present invention this limitation is overcome and a greatly increased number of periods during which the goods are pressed against the oscillating roll are attained without any increase in the number of pressure rolls themselves.

The method and means whereby this novel and useful effect is attained can best be understood by reference to the figures in which:

Figure 1 illustrates a partially schematic end view of the machine, and

Figure 2 illustrates a partially schematic side view of the machine.

A torsionally oscillating roll 1, is supported by a concentric shaft 2. This shaft 2 is suitably supported at one end by bearings 3 which may be positioned if desired, in the wall of a tank or container. The other end of the shaft 2, may be secured to a drive member 4 such as the device illustrated in my Letters Patent 2,604,503 for supplying a torsionally oscillating drive to the roller

2

1. Although not illustrated in the drawing, this latter end of the shaft 2 may also be supported in a bearing member. Disposed about the torsionally oscillating roll 1 are pressure rollers 5, 6, 7 and 8. These rolls, preferably four in number, are positioned parallel to, and press against the oscillating roll 1 in a manner hereinafter described. Each of these rolls 5, 6, 7 and 8 are supported on concentric shafts 9. These shafts extend from either end of the roll into journal members 10. These journal members which permit free rotation of the rolls 5, 6, 7 and 8 are in turn mounted on rectangular blocks 11 (see Figure 1).

The blocks are in turn slidably mounted in the rectangular sleeve element 12, having closed ends 13 and 14 and a longitudinal opening on the inside wall through which the shaft 9 passes. The rectangular blocks 11 are pressed towards the ends 13 by helical springs 15. One end of each spring 15 presses against the rectangular block 11, while the other end may engage slidable plate member 16 having a projecting guide element and stop 17. The plate element 16 may be adjustably positioned within the rectangular sleeve 12 by means of the lock nut 18 and the bolt 19. This bolt 19, which is threaded through the end 14 engages the bottom plate 16 to position it at desired points along the length of the sleeve member 12. The sleeve members 12, are in turn secured to a large plate element 20 with the sleeve element 12 positioned in such a manner as to align with the radii of the torsionally oscillating rotating roller 1. The plates 20 are in turn fitted with hub members 21 concentric with and freely rotatable on the shaft 2. Rigidly fixed to the plate 20 are downwardly projecting arms 22 and 22' having elongated holes 23 formed at their lower ends. Through these holes 23 project the pins 24 and 24' carried by the eccentric arms 25 and 25'. These eccentric arms 25 and 25' are mounted on the opposite ends of the shaft 26 which in turn is supported in bearings 27. A pulley 28 mounted preferably at the center of the shaft 26 is connected to the pulley 29 by means of the belt 30. The pulley 29 is in turn mounted on the shaft 31 which is rotated by the motor drive 32. Positioned at the top of this machine are a series of rolls including the idler rolls 33 and 34, feed rolls 35 and 36 and the dancer rolls 37 and 38. The cloth or fabric material 39 being treated enters the machine over the feed roll 35 under the dancer roll 37 and over the idler roll 33. The dancer roll 37 and 38 are provided to take up the slack which develops periodically as the upper pressure rolls move to and fro from their central position during oscillation of their axis about the axis of the torsionally oscillating roll 1. The cloth 39 passes into the machine from the idler roll 33 between the roll 1 and 8 and then continues around the roll 1 passing between it and the rolls 7, 6 and 5 successively. It then is passed over the idler roll 34 under the dancer roll 38 and out of the machine over the feed roll 36. Thus in the general operation of this machine, the cloth 39 which is fed into the machine is subjected to an oscillating motion as it passes about the torsionally oscillating rotating roll 1. In addition to this action it is subject to continued pressure action of the pressure rolls 5, 6, 7 and 8 arcuately oscillating about the roll 1, thus exerting a continued pressure onto the cloth between these rolls and the oscillating roll 1.

65 A specific example of the additional action obtainable by the structure set forth above will indicate the substantial nature of the improvement of this invention. Let us now suppose for example that we wish the goods treated to pass through the machine at the rate of five yards per minute and be subjected to forty periods of vibration under pressure corresponding to ten passes by the usual method.

Five yards per minute of travel of the goods correspond to three inches per second of forward travel. Therefore, if the group of pressure rolls is oscillated backward and forwards about the axis of the main oscillating roll, and at an angular amplitude corresponding to $1\frac{1}{2}$ inches of the periphery of the main oscillating roll 1, once per second, each linear increment of the goods will be squeezed twice in going under each pressure roll, or a total of eight squeezes instead of four. If the group of rolls is oscillated five times per second about the axis of roll 1, each linear increment of the goods will be squeezed ten times in going under each pressure roll or a total of forty times in one passage through the machine instead of the four squeezes to which it would be subjected in going through the machine in the usual manner.

Continuing the example, in the case of four inch diameter pressure rolls oscillating about the axis of a six inch diameter roll 1, the angle of oscillation would be 28.6 degrees, i. e. the angular amplitude of oscillation would have this value.

Having now described my invention, I claim:

1. In combination with means supplying a torsionally oscillating rotating drive, a roller mechanism comprising an oscillating rotating roller operatively coupled to said drive, a pressure roller positioned parallel to and pressed toward said oscillating rotating roller, and means operatively connected to said pressure roller providing an arcuate oscillation of said pressure roller about and in pressed contact with said oscillating rotating roller.

2. In combination with means supplying a torsionally oscillating rotating drive, a roller mechanism comprising an oscillating rotating roller operatively coupled to said drive, a pressure roller positioned parallel with said rotating roller, means resiliently pressing said pressure roller in tangential contact with said rotating roller, and means operatively connected to said pressure roller providing an arcuate oscillation of said pressure roll about and in pressed contact with said oscillating rotating roller.

3. In combination with means supplying a torsionally oscillating rotating drive, a roller mechanism comprising an oscillating rotating roller operatively coupled to said drive, a pressure roller positioned parallel with said rotating roller, means resiliently pressing said pressure roller in tangential contact with said rotating roller and reciprocating means operatively connected to said pressure roller providing in conjunction with said last mentioned means an arcuate oscillation of said pressure roll about and in pressed contact with said oscillating rotating roller.

4. In combination with means supplying a torsionally oscillating rotating drive, a roller mechanism comprising an oscillating rotating roller operatively coupled to said drive, a pressure roller positioned parallel to said rotating roller, means journalling said pressure roller adapted to permit displacement of said pressure roller arcuately and in substantial tangential contact with said rotating roller, spring means pressing said pressure roller against said rotating roller, and reciprocating means operatively connected to said pressure roller providing an arcuate oscillation of said pressure roller about and in pressed contact with said oscillating rotating roller.

5. In combination with means supplying a torsionally oscillating rotating drive, a roller mechanism comprising an oscillating rotating roller operatively coupled to said drive, a plurality of pressure rollers positioned parallel to said rotating rollers, journal means for said pressure rollers adapted to permit displacement of each pressure roller arcuately and in substantial tangential contact with said rotating roller, spring means pressing said pressure rollers against said rotating roller, and reciprocating means operatively connected to said journal means providing arcuate oscillation of said pressure roller about said oscillating rotating roller.

6. In combination with a torsionally oscillating rotating roller a pressure roller parallel to said rotating roller,

means journalling said pressure roller adapted to permit displacement of said pressure roller arcuately and in substantial tangential contact with said rotating roller, spring means pressing said pressure roller against said rotating roller, and reciprocating means operatively connected to said journal means providing arcuate oscillation of said pressure roller about said oscillating rotating roller.

7. In combination with a torsionally oscillating rotating roller, a pressure roller positioned parallel to and pressed toward said oscillating rotating roller, and means operatively connected to said pressure roller providing an arcuate oscillation of said pressure roller about and in pressed contact with said oscillating rotating roller.

8. In combination with a torsionally oscillating rotating roller a plurality of pressure rollers positioned parallel to and in pressed contact with said oscillating rotating roller, and means operatively connected to said pressure rollers, providing arcuate oscillations of said pressure rollers about and in pressed contact with said oscillating rotating roller.

9. In combination with a torsionally oscillating rotating roller a plurality of pressure rollers positioned parallel to said rotating roller, journals securing the ends of said pressure rollers for rotation, means slideably mounting said journals for displacement in alignment with radii of said torsionally oscillating rotating roller, spring means pressing said journals toward said rotating roller, and means operatively connected to said means mounting said journals providing arcuate oscillation of said pressure rollers about and in pressed contact with said oscillating rotating roller.

10. A combination as set forth in claim 9 wherein said means providing arcuate oscillation comprises freely rotatable plates fixed to said means mounting said journals having hubs coaxially mounted with said rotating roller and a drive means for providing arcuate oscillations to said plate.

11. In combination with a torsionally oscillating rotating roller four pressure rollers positioned parallel to said rotating roller, journals securing the ends of said pressure rollers for rotation, sleeve members slideably mounting said journals for displacement in alignment with radii of said torsionally oscillating rotating roller, spring means pressing said journals toward said rotating roller, a freely pivotable pair of plates each mounting the sleeve members at one end of said pressure rollers and having a hub coaxial with said rotating roller, and means providing an oscillation of said plates about said hub.

12. A combination as set forth in claim 1 wherein said rotating roller oscillates at a high frequency and at a small amplitude relative to the frequency and amplitude of the pressure roller.

13. In combination with means supplying an oscillatable rotatable drive, a roller mechanism comprising an oscillating rotating roller operatively coupled to said drive, a pressure roller positioned parallel with said rotating roller, means resiliently pressing said pressure roller in tangential contact with said rotating roller and reciprocating means operatively connected to said pressure roller providing in conjunction with said last-mentioned means an arcuate oscillation of said pressure roll about and in pressed contact with said oscillating rotating roller.

14. In combination with an oscillatable rotatable roller, a pressure roller positioned parallel to and pressed toward said oscillating rotating roller, and means operatively connected to said pressure roller providing an arcuate oscillation of said pressure roller about and in pressed contact with said oscillating rotating roller.
